UNITED STATES PATENT OFFICE.

MICHAEL CLARKSON, OF CHICAGO, ILLINOIS.

APPARATUS USED IN THE CONSTRUCTION OF FIRE-HYDRANTS AND THE LIKE.

1,030,384.

Specification of Letters Patent. Patented June 25, 1912.

Application filed April 24, 1909. Serial No. 492,047.

To all whom it may concern:

Be it known that I, MICHAEL CLARKSON, a citizen of the United States, residing at Chicago, in the county of Cook and State 5 of Illinois, have invented new and useful Improvements in Apparatus Used in the Construction of Fire-Hydrants and the Like, of which the following is a full, clear, and exact description.

10 My invention relates more particularly to the apparatus for molding and constructing the concrete upper portion of fire-hydrant basins, and the like.

15 The object of said invention is to provide means for the construction of such basins in an economical and expeditious manner; whereby a platform may be constructed between the top and bottom of the basin that divides the same into an upper 20 and lower chamber, also the contracted upper portion of said basin, and also an integral top or surface covering for the same.

25 A further object of my invention is to make these improved means knock-down and capable of being easily set up, and after use taken to pieces and removed through the hatchways of the platform and surface covering. This I accomplish by the means hereinafter fully described, and as particularly pointed out in the claims.

30 In the drawings Figure 1 is a vertical section of an incomplete hydrant basin illustrating the way in which my improved apparatus is set up for use. Fig. 2 is a similar section of the upper portion thereof taken on dotted line 2, 2, Fig. 1. Fig. 3 is a vertical section similar to Fig. 1 showing the upper portion of the completed basin, in the construction of which my invention is 40 adapted to be used. Fig. 4 is a horizontal section of my improved apparatus taken on dotted line 4, 4, Fig. 3 showing the apparatus for making the platform, in position. Fig. 5 is a perspective view of a collapsible 45 former for making the throat or upper part of the said basin or well. Fig. 6 is a perspective view of the templet for making the trap door in the platform of the same. Fig. 7 is a plan view of the templet used for 50 making the opening in the platform for the passage of the hydrant pipe. Fig. 8 is a vertical section of a modified construction of a hydrant-basin, in the construction of which my improvements may be used. Fig. 55 9 is a vertical section of an ordinary catch basin in the construction of the contracted

upper portion of which part of my invention may be used.

Fig. 3 of the drawings shows the upper portion of a hydrant-basin or well in the 60 construction of which my improved devices are adapted to be used. The hydrant basin referred to may have the walls A of the lower portion built of brick. I prefer, however, to make them of concrete. If made of 65 brick the top course terminates a suitable distance below the surface of the walk or road and above this brick the basin is constructed of cement or concrete walls B. The inner surface of this concrete portion contracts as it extends upward, and the top of the basin is closed by an integral floor C. Near one side of the basin this floor C is provided with a suitable opening a, down through which the supply-pipe b of the 70 hydrant D extends. The basal flanges of the hydrant rest upon the edges of said opening and cover it, and in order to make said opening water-tight, tarred paper or other suitable packing is placed beneath said flanges. 75 Floor C is also provided with a rectangular elliptical or other suitable shaped hatchway, the edges of which are beveled, and which is closed by a suitable trap-door d, having corresponding oppositely beveled edges. 80 One end of said hatchway connects, preferably, with said opening, but it is obvious, 85 may be disconnected therefrom if desired.

A suitable distance below floor C; preferably at the lower end of the contracted upper portion of the basin the latter is provided with an integral cement or composite stone platform E that divides the interior of the same into an upper and lower chamber. This platform is provided with an 90 opening e similar to that in the floor C, with which it alines, and also with a corresponding hatchway which is closed by a stone 95 trap-door F that corresponds to trap-door d located directly above in said floor. 100

The drawings show a hydrant-pipe and show it between floor C and platform E surrounded by suitable insulation, but the subject-matter of this application is not concerned with this insulation nor the catch-basin, *per se*, but is confined principally to the means for molding the upper portion of the basin just described.

After building the walls of the lower portion of the basin with brick or concrete to 110 the plane of the platform E, I build a temporary platform consisting of a center

plate, which is made of two sections 2 and 3, and two side plates 4, 4. The meeting edges of the two sections of the center-plate abut in the vertical plane of the segment of opening *e* nearest the center of the basin, and I prefer to make the orifice in this temporary platform registering with the opening *e* preferably in the meeting edge of the shorter section of said center plate. The longer section of said center plate extending from said orifice diametrically across the basin is provided with a hatchway, which is, preferably, of an elongated rectangular or of an elliptical shape, and is of sufficient dimensions to permit of the passage of the body of a workman down through said platform *E*, when the latter has sufficiently set to support itself to enable the temporary platform and its supporting structure to be knocked down and removed. When the center and side plates of the platform are assembled their outer edges describe a circle corresponding in circumference to the inner diameter of the basin, and they are supported by cross-beams 5, 5, arranged transversely under their ends; which latter, are, in turn, supported by uprights 6, 6, whose lower ends rest upon a horizontally disposed plank 7 that rests upon and is supported at its ends by the heads on the upper ends of the vertically adjustable members of the jack-screws 8, 8. The meeting edges of the sections of the center-plank of said temporary platform rest upon a cross-bar, 9, which, in turn, is supported at its center of length by an upright, 10, standing upon plank 7. The employment of these jack-screws, 8, enables me to obtain the correct vertical adjustment of the parts of the temporary platform in the proper horizontal position to construct the platform *E* in the proper plane. After this temporary platform has been built, I surround the orifice in section 3 of its center-plate (registering with and corresponding in diameter to opening *e* in platform *E*), with a cylindrical templet 11. This templet, 11, is provided with the basal flange that rests upon the temporary platform; the length of its cylindrical portion corresponds to the thickness of the completed platform *E*, and the side thereof nearest the center of the basin is provided with a removable longitudinally extending section 12, the width of which corresponds to the width of the hatchway, substantially as shown in Fig. 4 of the drawings.

The trap-door *F* for the hatchway in said platform, *E*, is made with the same material at the same time as said platform. I employ a U-shaped sheet metal templet 13 for this purpose, whose lower edges conform in length and width to the hatchway made in the center-plate of the temporary platform, and when assembling the devices

for constructing the platform *E* I place under this templet a sheet metal plate 25 that corresponds in shape to said trap-door, but is of such increased dimensions that it laps over and rests upon the edges of the hatchway in said center plate. The sides of this templet 13, are inclined outward from the lower edges thereof, and the height of the same corresponds to the thickness of platform *E*, when made. When the parts of the temporary platform, and templets 11 and 13, are thus properly assembled in the manner and positions hereinbefore stated, the cement or other plastic concrete material is spread over and built upon the temporary platform and likewise in templet 13 to the proper height, and then allowed to set and harden. Before the spreading of the cement or concrete is done, however, I prefer to place a couple of cylindrical sleeves, 26, upon the temporary platform; one, just beyond the end of the templet 13 farthest from the supply-pipe of the hydrant, and the other diametrically opposite on the other side of said pipe. These cylinders provide openings for the insertion of uprights 14, 14, that rest upon the lower temporary platform after the concrete platform has been built. The upper ends of these uprights are made to support cross-bars 15, that come under and support the ends of the center and side-plates of an upper temporary platform upon which the cover or floor closing the upper end of the hydrant basin is built. This upper temporary platform is, preferably less in diameter than the lower temporary platform and is likewise constructed of a center-plate comprising two sections, 16 and 17, and two side plates, 18, 18, and has a templet, 19, for the pipe-opening in said floor, and a templet 20 for the trap-door and hatchway of said floor that are constructed substantially like corresponding parts used in connection with the lower temporary platform. After the parts of said upper temporary platform have been properly assembled and arranged in place, and the templets, 19, and 20, properly placed thereon, I drop down over the same a circular former 21, which latter consists of a series of longitudinally disposed sections, whose vertical edges, at about their centers of length, are provided with knuckles that are connected by removable pintles 22; which latter can be easily inserted and removed, either to set-up or knock-down said former. The upper edges of each or several of the segmental sections are provided with inturned lugs 23 which, when the former is dropped into operative position catch upon the edges of the upper platform and suspend the former in concentric position. This former is so constructed that it is less in diameter at its upper end than at its lower, and it is

of such length that its lower edges terminate in the horizontal plane of the upper surface of the completed platform E.

After the concrete platform E, has been built up, the concrete material is dumped into the excavation around the former and tamped down, and then after this has been satisfactorily done the concrete is spread over the upper platform until the upper surface is level with the roadway or pavement, and the templet 20 is filled even with its upper edges. The concrete is then permitted to set for several days, until it becomes so hard that the floor over the top of the basin can be walked upon. The trap-door in said upper floor is then removed, and the workman reaches down therethrough and lifts the trap-door in the concrete platform, E, and then lowers himself through both hatchways into the lower chamber of the basin. The jack-screws are then lowered, and the uprights removed and the several parts of the temporary platform, are separated and handed up through the hatchways to a companion above. When the center-plate of the lower temporary platform is removed, the uprights 14, 14, fall down through the sleeves in which their lower ends were seated, and their removal permits the cross-bars 15, and the center and side-plates of the upper temporary platform to fall apart, so that, by reaching down from above they can be easily removed. One or more of the pintles 22 connecting the sections of the former are then removed, and said sections are collapsed one upon the other so as to fold the former into such compass that it can be easily withdrawn from the hatchway in the floor 7. This done the insulating material is then put in position, and the sleeves 26 removed and the openings left thereby filled with cement as shown in Fig. 3 of the drawings, and then the supply pipe of the hydrant may be passed down through the same, or, if said hydrant is already in place, the casing inclosing said pipe, which is provided with a longitudinally disposed removable section, is made to surround the said supply-pipe, between the top of the platform E and the basal flange of the hydrant, and the annular space filled in with insulating material, substantially as shown and as fully described in the companion application for Letters Patent of the United States for the said catch basin filed April 24th, 1909, Serial Number 492,046.

In Fig. 8 I show a modified form of a hydrant-basin which is adapted to be constructed by my improved device with the exception of the upper temporary platform. In this modified hydrant-basin I provide the upper end or contracted mouth of the basin with an angle iron rim R, the basal flange of which is inserted in the surround-

ing concrete, and I cover this rim with a metal cover, J, whose edges lap over and are seated upon the upper edge of said rim. The only difference in the construction of the former for affecting the contraction of the upper portion of this modified hydrant basin is that the upper edges of the sections thereof should be provided with outwardly projecting lugs that rest upon the upper edges of said angle-iron rim, and the latter, before the concrete was poured into the surrounding excavation, will be supported by brick or pieces of wood resting upon the brick wall of the lower portion of the hydrant-basin so as to bring the upper edges of said rim up to the level of the street or pavement.

In Fig. 9 of the drawings I show how the former can be used without either upper or lower temporary platform or templets used in conjunction therewith, to construct the upper contracted end of an ordinary catch-basin. When the former is used for this purpose it is, preferably, comparatively greater in length than when used in the construction of hydrant-basins. In making the upper portions of these catch basins, an iron rim K, for the mouth of the same, is placed in position above and concentric to the vertical axis of the lower portion of the catch basin, and is propped up so that its upper edge is level with the grade of the surrounding street or pavement, by means of brick or pieces of wood inserted under the basal flanges of said rim and resting and supported upon the upper end of the brick lower portion of the catch-basin. The former, L, is collapsed and inserted down through the rim until it can be opened out and expanded to its fullest extent whereupon it is lowered until the lugs k, k, rest upon the rabbeted seat for the cover in the upper edge of said rim. In this position the lower edges of said former should depend down into and past the upper edge of the walls of the lower portion of the basin, and when the concrete is dumped into the excavation surrounding said rim and former and tamped down the upper contracted portion of the basin will be completed. When this kind of a catch-basin is made it is only necessary, after the concrete has set to collapse and remove the former in the manner hereinbefore indicated.

From the foregoing descriptions it will be observed that one of the principal advantages accomplished by the use of my improved device is that ordinary common laborers, such as are engaged in the construction of the surrounding concrete pavement or side walk may be employed, as all that it is necessary to do is to set up and knock-down the parts of my improved devices and tamp in the concrete material. The necessity for the employment of expert

masons to make the contracted upper portions of the basin is entirely obviated, and, having reference to the preferred form of basin in the construction of which my improvements are designed to be used, a hydrant-basin is made that dispenses with the employment of considerable labor and material to keep the supply-pipe and its connections from freezing during the colder parts of the year, substantially as set forth in the said accompanying application for Letters Patent of the United States, hereinbefore referred to.

What I claim as new is:—

15 1. Apparatus for building hydrant basins comprising a temporary platform located below the top of the basin and consisting of several plates arranged side by side, one of which is provided with an opening there-
20 through, and with a hatchway, and templets supported by said platform for defining said opening and hatchway and means for supporting said plates.

25 2. Apparatus for building hydrant-basins comprising a knockdown temporary platform adapted to be located below the top of the basin, and having an opening therein for the passage of the supply pipe of the hydrant and a hatchway therethrough, a tem-
30 plet conforming to and extending said opening through the finished platform and a templet for defining the edges of said hatch-
way therein.

35 3. Apparatus for building hydrant basins comprising a circular shaped collapsible former consisting of several longitudinally disposed sections removably connected together, a temporary knockdown platform adapted to be located in said basin below the
40 lower edges of said collapsible former and a temporary knockdown platform at the upper end of said former.

45 4. Apparatus for building hydrant basins comprising a circular shaped collapsible former consisting of several longitudinally disposed sections removably connected together, a temporary knockdown platform adapted to be located in said basin below the lower edges of said collapsible former and a
50 temporary knockdown platform at the upper end of said former and removable means supported by said lower platform for holding up said upper platform.

55 5. Apparatus for building hydrant basins comprising a circular shaped collapsible former consisting of several longitudinally disposed sections removably connected together, a temporary knockdown platform adapted to be located in said basin below the
60 lower edges of said collapsible former, removable means for supporting said platform,

and a temporary knockdown platform at the upper end of said former.

6. Apparatus for building hydrant basins comprising a circular shaped collapsible former consisting of several longitudinally disposed sections removably connected together, a temporary knockdown platform adapted to be located in said basin below the lower edges of said collapsible former, removable means for supporting said platform, and a temporary platform at the upper end of said former and removable means including uprights supported by said lower platform for holding up said upper plat- 75 form.

7. Apparatus for building hydrant basins comprising a circular shaped collapsible former consisting of several longitudinally disposed sections removably connected together, a temporary knockdown platform adapted to be located in said basin below the lower edges of said collapsible former, removable means for supporting said platform, and a temporary platform at the upper end of said former and removable means including uprights, whose lower ends are loosely incased in sleeves for holding up said upper platform. 80

8. Apparatus for building hydrant basins comprising a temporary platform consisting of several plates the central one of which is made in two sections, the end edges of which abut, and in one of which sections the principal part of the opening for the passage of the supply-pipe and the other of said sections is provided with a hatchway, and suitably supported cross-bars for supporting said plates. 90

9. Apparatus for building hydrant basins comprising a temporary platform consisting of several plates the central one of which is made in two sections and end edges of which abut, and in one of which sections the principal part of the opening for the passage of the supply-pipe and the other of said sections is provided with a hatchway, a cylindrical templet conforming in diameter to and mounted upon said section over said opening and a suitable hatchway templet for extending upward the edges of said hatchway, cross-bars for supporting said plates, and adjustable means for supporting said cross-bars. 100

In testimony whereof I have hereunto set 115 my signature this 9th day of November, 1911.

MICHAEL CLARKSON.
